(57) **CLAIM**

I claim the ornamental design for a clamshell-style valve knob cover lockout device, as shown and described.

DESCRIPTION

FIG. 1 shows a general perspective view of the invention in a closed position.

FIG. 2 shows a general perspective view of the invention in an open position.

FIG. 3 is a front view of an embodiment in the closed position. FIG. 4 is a back view of an embodiment in the closed position. FIG. 5 is a right side view of an embodiment in the closed position.

FIG. 6 is a left side view of an embodiment in the closed position.

FIG. 7 is a top view of an embodiment in the closed position. FIG. 8 is a bottom view of an embodiment in the closed position.

FIG. 9 is a front view of an embodiment in the open position. FIG. 10 is a back view of an embodiment in the open position. FIG. 11 is a right side view of an embodiment in the open position.

FIG. 12 is a left side view of an embodiment in the open position.

FIG. 13 is a top view of an embodiment in the open position; and,

FIG. 14 is a bottom view of an embodiment in the open position.

The broken line showings of a sample valve and pipe extending therefrom are directed to environment and are for illustrative purposes only; the broken lines form no part of the claimed design.
